CIRCUIT INTERRUPTER

Russell E. Frink, Pittsburgh, Pa., assignor to
Westinghouse Electric Corporation, East Pittsburgh,
Pa., a corporation of Pennsylvania

Application September 27, 1947, Serial No. 776,502

14 Claims. (Cl. 200—147)

1

This invention relates to circuit interrupters in general, and more particularly to arc-extinguishing structures therefor.

A general object of my invention is to provide an improved circuit interrupter of the type utilizing a blowout magnetic structure in which a series coil is inserted in the circuit during at least a portion of the opening operation to energize or magnetize the included blowout structure. As is well known by those skilled in the art, such blowout structure operates to move the arc into any desired interrupting structure to more readily effect its extinction therein.

A further object is to provide an improved circuit interrupter in which the blowout windings are more rapidly inserted into series circuit to decrease the overall time of operation of the interrupter.

Still a further object is to provide an improved blowout structure for a circuit interrupter in which at least two separate windings are used with the blowout structure, and improved interrupting means are provided to interrupt the transfer arc upon the insertion of the second blowout coil into series circuit, the transfer arc being the arc in parallel with the second blowout coil.

Still a more specific object is to provide an improved circuit interrupter of the air-break type in which a conducting probe is disposed intermediate the ends of the arc chute. Preferably, the probe is electrically connected to an auxiliary fine winding coil disposed about the blowout structure in conjunction with a relatively few-turn heavy winding coil. Thus, the transfer arc, which must be interrupted upon the insertion of the fine winding coil into series circuit, is more readily extinguished by the utilization of part of the arc chute structure.

Further objects and advantages will readily become apparent upon reading the following specification taken in conjunction with the drawings, in which:

Figure 1 is a side elevational view, partially in vertical section, of an improved air-break type of circuit interrupter embodying my invention and shown in the closed circuit position;

Fig. 2 is a transverse vertical sectional view taken along the line II—II of Fig. 1 as viewed in the direction of the arrows;

2

Fig. 3 is a fragmentary plan sectional view taken along the line III—III of Fig. 1 looking in the direction of the arrows, and

Fig. 4 is a diagrammatic view of the electric connections involved in the operation of my improved circuit interrupter.

Any circuit breaker, no matter what its maximum interrupting rating, must be able to interrupt currents of all magnitudes from zero up to and including its rating. A comparatively large number of turns is necessary in the blowout coil of an air-magnetic breaker (8 or 10 or preferably more) to interrupt the load and overload currents. It is not practical to carry the continuous current through the blowout coil because of heating, and the problem then presents itself of getting the coil into the circuit as rapidly as possible during interruption.

An arc chute having a high k. v. a. rating is necessarily physically larger than an arc chute having a lower k. v. a. rating. If both arc chutes have the same flux density over the interrupting region, the total flux threading the coil in the larger chute will be greater in proportion to the areas of the magnetic pole pieces. When the field is energized a voltage will appear across the terminals of the coil which is equal to

$$E = \frac{Nd\theta}{dt} \times 10^{-8}$$

where N is the number of turns in the blowout coil and

$$\frac{d\theta}{dt}$$

is the time rate of change of the flux threading the coil. This voltage appears immediately when the current is transferred to the coil and is in such a direction as to oppose the transfer. Introducing the current into the coil is then a problem of interrupting the section of arc across the coil terminals and is an identical problem to that found in interrupting any reactive circuit. The interrupting voltage will be proportional to N^k where N is the number of turns in the blowout coil and k is a factor between 1 and 2. If the magnetic circuit is a tight iron circuit and highly saturated, k would be approximately 1, but if the magnetic circuit is air and coupling is near unity then k would be 2. The magnetic circuit

in an air circuit breaker is iron with a large air gap so k will lie between the two extremes. Previous experience in circuit interruption shows that the lower the voltage to be interrupted, the more current a given interrupter can handle. Reducing the number of turns will increase the current that can be transferred to the coil by a factor of

$$I_2 = I_1 \left(\frac{N_1}{N_2} \right) k$$

where

$$\frac{N_1}{N_2}$$

represents the factor by which the number of turns is reduced and k is a number between 1 and 2.

A structure will now be described which will take advantage of the principles just set forth in a novel manner that will enable it to handle high currents and still introduce a sufficient number of turns into the circuit to give the high field strengths necessary.

Referring to the schematic diagram, as shown in Fig. 4, the reference numerals 1 and 2 indicate the line terminals of a protected circuit which is controlled by the operation of a circuit interrupter generally designated by the reference numeral 3. Upon the separation of the main contacts 4, 5 of the circuit interrupter 3, an arc 6 is initially established. Because of the loop circuit provided, more fully described hereinafter, the initial arc 6 is readily transferred to the arcing horns 8, 9 to thereby insert into series circuit a relatively heavy winding blowout coil 10 of few turns. The energization of the blowout coil 10 sets up a magnetic field transverse to the spaced plate structure generally designated by the reference numeral 11 and forces the arc, designated by the reference numeral 12, up into the plate structure 11.

The upward moving arc 12 contacts the conducting probe 13, the latter being electrically connected by a conductor 14 to a relatively fine winding blowout coil 15 which is disposed about the same bight portion 16 of the blowout structure as is disposed the blowout coil 10 of relatively few turns. Thus the two coils 10, 15 have cores of substantially the same cross-sectional area. Preferably they are positioned closely together upon the bight portion 16 of the blowout structure so that they are tightly coupled together, and all the flux of the coil 10 passes through the core of the coil 15. The position of the arc is now designated by the reference numeral 17, immediately after it has contacted the probe 13. The blowout coil 10 is quickly and easily transferred into series circuit because it is composed of few turns, say two or three. While this coil 10 will not supply the strong field necessary for interruption, it is strong enough to move the arc 12 up into the plate structure 11. The magnetic field supplied by the blowout coil 10 causes the section of arc between the arc horn 8 and the probe 13, designated by the reference numeral 18, to rise up into the portion 19 of the plate structure 11 disposed between the probe 13 and the arc horn 8. This movement of the arc 18 into the plate structure 11 raises the arc voltage across the section of the arc 18 to a value higher than the voltage between arcing horns 8, 9 would be if the current were flowing through the second relatively fine winding blowout coil 15. The result is that the arc 18 is extinguished and the

current transfers to the second auxiliary blowout coil 15, and interruption of the circuit is accomplished with the blowout coils 10, 15 in series acting as one coil.

5 The combined magnetic effect produced by the joint action of the blowout coils 10, 15 serves to move the arc portion 20 between the arcing horns 13, 9 up into the portion 21 of the plate structure 11 to thereby effect the extinction of the arc portion 20. When this is accomplished the circuit is interrupted.

From the foregoing discussion of the principles of my invention taken in connection with the diagrammatic view of Fig. 4, it will be readily apparent how the invention may be applied to a commercial type of circuit interrupter set forth in Figs. 1-3, the operation and method of arc rupture within the plate structure being set forth and described broadly in U. S. patent application filed December 15, 1943, Serial No. 514,362, now U. S. patent 2,442,199, issued May 25, 1948 to Robert C. Dickinson and Russell E. Frink and assigned to the assignee of the instant application.

15 20 25 30 35 40 45 50 55 60 65 70 75 80 85 90 95 100

From the foregoing discussion of the principles of my invention taken in connection with the diagrammatic view of Fig. 4, it will be readily apparent how the invention may be applied to a commercial type of circuit interrupter set forth in Figs. 1-3, the operation and method of arc rupture within the plate structure being set forth and described broadly in U. S. patent application filed December 15, 1943, Serial No. 514,362, now U. S. patent 2,442,199, issued May 25, 1948 to Robert C. Dickinson and Russell E. Frink and assigned to the assignee of the instant application.

25 30 35 40 45 50 55 60 65 70 75 80 85 90 95 100

Preferably the structure involved in the circuit interrupter set forth in Figs. 1-3 includes a main contact structure generally designated by the reference numeral 23, a blowout structure generally designated by the reference numeral 24 and a spaced slotted ceramic plate structure generally designated by the reference numeral 11. In the closed circuit position of the interrupter, as shown in Fig. 1, the electric circuit therethrough includes a conducting terminal stud 26 extending through an insulating terminal bushing 27. The terminal stud 26 is electrically connected, as by a thread connection, to a main stationary contact plate 28. The lower end of the contact plate 28 forms a main stationary contact 29, which is contacted, in the closed circuit position, by a conducting bridging member 30, the lower end 31 of which makes engagement with a second main stationary contact 32.

Preferably, the second main stationary contact 32 is a portion of a second contact plate, not shown, which is electrically connected to the other terminal stud of the interrupter, not shown, as is well known by those skilled in the art.

A rotatable contact arm 33 carries the bridging member 30 upon studs 34, 35, compression springs 36, 37 being provided to obtain the requisite contact pressure in the closed circuit position. Associated with the plate 28 is an arcing contact structure 38 operable to establish an arc 6 between the arcing contacts 4, 5 when separated. For purposes of illustration the arc 6 is shown in Fig. 1 even though the arcing contacts 4, 5 are in the closed position. Also the reference characters are made to correspond, as far as possible, with the reference characters already discussed in connection with Fig. 4.

Upon opening rotative movement of the contact arm 33 the arc 6 is initially established between the arcing contacts 4 and 5. Because of the loop circuit provided between the terminal studs the arc 6 bows upwardly to contact the arcing horn 8 and the arcing horn 9 to thereby cause the insertion into series circuit of the heavy winding blowout coil 10, more clearly shown in Fig. 3. Since the coil 10 is composed of a few turns, say two or three, it is quickly and easily transferred into series circuit.

The energization of the heavy winding blowout coil 10 causes a magnetic field to build up in the blowout structure 24, the magnetic field

passing transversely through the plate structure 11 between the magnetic pole plates 39, 40. The transverse magnetic field 41 (Fig. 3) established between the pole plates 39, 40 reacts upon the arc 12 to move it upwardly and into engagement with the probe 13. It will be noted that a conductor 14 electrically connects the probe 13 with the relatively fine winding blowout coil 15 which is wound around the bight portion 16 of the blowout structure 24. Preferably the tightly coupled coils 10, 15 have substantially the same core area, with the entire flux of coil 10 passing through coil 15. Both coils 10, 15 are wound about the same iron yoke 16 of the magnet frame.

The reference numeral 17 indicates the position of the arc when it initially strikes the probe 13. Thereafter, it is divided into two arc portions 18, 20 which respectively move upwardly into the plate portions 19, 21 of the plate structure 11. The plate structure 11 consists of a plurality of spaced slotted ceramic plates 42 which do not evolve gas upon being subjected to the action of an electric arc. Each rectangularly-shaped plate 42 has a slot 43 formed therein, as more clearly shown in Fig. 2. The upper end of the slot 43 is off center, and the plates are alternately disposed so that the arc is elongated laterally as it moves toward the upper ends of the several slots 43.

The magnetic field 41 continues to move the arc portions 18, 20 upwardly to effect their extinction in the closed ends of the slots 43. Preferably, the plates 42 are spaced a relatively short distance apart by insulating spacer strips 44. The aforesaid patent application may be referred to for the details of the plate structure 11, as well as for the theory of arc extinction. It suffices here to state that the magnetic field 41 set up by the energization of the relatively heavy winding blowout coil 10 effects the extinction of the transfer arc 18 between the arcing horns 8, 13 within the portion 19 of the plate structure 11. As previously mentioned the flux produced by the coil 10 threads coil 15 and induces a voltage which appears at the probe 13 and is in such a direction as to make the arc seek the horn 13.

The ready extinction of the arc portion 18 causes both coils 10, 15 to be in series circuit and to cumulatively energize the blowout structure 24. The cumulative action readily moves the arc portion 20 upwardly into the plate structure 21 to effect the extinction of the arc 20 therein.

Although I have shown and described a specific structure, it will be clearly understood by those skilled in the art that changes and modifications may readily be made therein without departing from the spirit and scope of the appended claims.

I claim as my invention:

1. Arc-extinguishing means including an interrupting section having a conducting probe disposed intermediate the ends thereof so that interrupting portions exist on both sides of the probe, means for establishing an arc, a magnetic circuit including magnetizable material for acting upon the arc, a pair of blowout coils shorted out in the closed circuit position of the interrupter and having substantially the same core area wound about the magnetizable material, one of the blowout coils having relatively few turns and the other having a greater number of turns, means for first inserting into series circuit the blowout coil of few turns, one end of the blowout coil of greater turns being connected to the conducting probe, and the established arc mov-

ing into the interrupting section into engagement with the probe to insert into series circuit both blowout coils.

2. A circuit interrupter including an interrupting section, a pair of stationary arc horns at opposite ends of the interrupting section, a probe disposed intermediate the ends of the interrupting section so that interrupting portions exist on both sides of the probe, means for establishing an arc, blowout means including a pair of blowout coils connected in series and shorted out in the closed circuit position of the interrupter, one of the arcing horns being connected intermediate the coils, and the probe being connected to the end of one of the coils, the arrangement functioning to successively insert the coils into series circuit with the transfer arc of the said one of the coils being interrupted in the portion of the interrupting section between the probe and said one of the arcing horns.

3. A circuit interrupter including an interrupting section, a pair of stationary arc horns at opposite ends of the interrupting section, a probe disposed intermediate the ends of the interrupting section so that interrupting portions exist on both sides of the probe, means including a pair of separable contacts for establishing an arc, blowout means including a pair of blowout coils connected in series and shorted out in the closed circuit position of the interrupter, one of the arcing horns being connected intermediate the coils, and the probe being connected to the end of one of the coils, one of the separable contacts being connected to the other end of the other of the coils, the other of the separable contacts being connected to the other arcing horn, the arrangement functioning to successively insert the coils into series circuit with the transfer arc of the said one of the coils being interrupted in the portion of the interrupting section between the probe and said one of the arcing horns.

4. In a circuit interrupter, an interrupting section, means for establishing an arc, blowout means including a magnetic circuit composed in part of magnetizable material, a pair of blowout coils of substantially the same core area wound about the magnetizable material and shorted out in the closed circuit position of the interrupter, means for first inserting into series circuit one of the blowout coils, a probe disposed in the interrupting section intermediate the ends thereof so that interrupting portions exist on both sides of the probe, the probe being connected to the end of the other of the two blowout coils, and one of said portions of the interrupting section, one end of which is defined by the probe, serving as a transfer arc interrupting section to facilitate the insertion of the said other of the two blowout coils.

5. In a circuit interrupter, an interrupting section, means for establishing an arc, blowout means including a magnetic circuit composed in part of magnetizable material, a pair of blowout coils of substantially the same core area wound about the magnetizable material and shorted out in the closed circuit position of the interrupter, means for first inserting into series circuit one of the blowout coils, a probe disposed in the interrupting section intermediate the ends thereof so that interrupting portions exist on both sides of the probe, the probe being connected to the end of the other of the two blowout coils, one of said portions of the interrupting section, one end of which is defined by the probe, serving as a transfer arc interrupting section to facilitate the in-

sertion of the said other of the two blowout coils, and said one of the blowout coils having relatively few turns and the other of the blowout coils having more turns.

6. A circuit interrupter including an interrupting section, a pair of stationary arc horns at opposite ends of the interrupting section, a probe disposed intermediate the ends of the interrupting section, means for establishing an arc, blowout means including a pair of tightly coupled blowout coils connected in series and shorted out in the closed circuit position of the interrupter, one of the arcing horns being connected intermediate the coils, the probe being connected to the end of one of the coils, the arrangement functioning to successively insert the coils into series circuit with the transfer arc of the said one of the coils being interrupted in the portion of the interrupting section between the probe and said one of the arcing horns, and said one of the blowout coils having more turns than the other of the blowout coils.

7. A circuit interrupter including an interrupting section, a pair of stationary arc horns at opposite ends of the interrupting section, a probe disposed intermediate the ends of the interrupting section, means including a pair of separable contacts for establishing an arc, blowout means including a pair of tightly coupled blowout coils connected in series and shorted out in the closed circuit position of the interrupter, one of the arcing horns being connected intermediate the coils, and the probe being connected to the end of one of the coils, one of the separable contacts being connected to the other end of the other of the coils, the other of the separable contacts being connected to the other arcing horn, the arrangement functioning to successively insert the coils into series circuit with the transfer arc of the said one of the coils being interrupted in the portion of the interrupting section between the probe and said one of the arcing horns, and said one of the blowout coils having more turns than the other of the blowout coils.

8. A circuit interrupter including means for establishing an arc, arc-extinguishing means including an arc chute composed mainly of insulating material including a plurality of spaced insulating portions against the edges of which the arc is forced, a conducting probe disposed intermediate the ends of the arc chute so that insulating portions exist on both sides of the probe, a magnetic circuit including magnetizable material for acting upon the arc, a pair of blowout coils shorted out in the closed circuit position of the interrupter and having substantially the same core area wound about the magnetizable material, one of the blowout coils having relatively few turns and the other having a greater number of turns, means for first inserting into series circuit the blowout coil of few turns, one end of the blowout coil of greater turns being connected to the conducting probe, and the established arc moving into the arc chute into engagement with the probe to insert into series circuit both blowout coils.

9. A circuit interrupter including means for establishing an arc, arc-extinguishing means including an arc chute composed mainly of insulating material including a plurality of spaced insulating portions against the edges of which the arc is forced, a pair of stationary arc horns disposed at opposite ends of the arc chute, a conducting probe disposed intermediate the ends of the arc chute so that insulating portions exist

on both sides of the probe, blowout means including a pair of blowout coils connected in series and shorted out in the closed circuit position of the interrupter, one of the arcing horns being connected intermediate the coils, and the probe being connected to the end of one of the coils, the arrangement functioning to successively insert the coils into series circuit with the transfer arc of the said one of the coils being interrupted in the insulating portion of the arc chute between the probe and said one of the arcing horns.

10. A circuit interrupter including a pair of separable contacts for establishing an arc, arc-extinguishing means including an arc chute composed mainly of insulating material including a plurality of spaced insulating portions against the edges of which the arc is forced, a conducting probe disposed intermediate the ends of the arc chute so that insulating portions exist on both sides of the probe, a pair of stationary arc horns at opposite ends of the arc chute, blowout means including a pair of blowout coils connected in series and shorted out in the closed circuit position of the interrupter, one of the arcing horns being connected intermediate the coils, the probe being connected to the end of one of the coils, one of the separable contacts being connected to the other end of the other of the coils, the other of the separable contacts being connected to the other arcing horn, the arrangement functioning to successively insert the coils into series circuit with the transfer arc of said one of the coils being interrupted in the portion of the arc chute between the probe and said one of the arcing horns.

11. A circuit interrupter including means for establishing an arc, arc-extinguishing means including an arc chute composed mainly of insulating material including a plurality of spaced insulating portions against the edges of which the arc is forced, a conducting probe disposed intermediate the ends of the arc chute so that insulating portions exist on both sides of the probe, blowout means including a magnetic circuit composed in part of magnetizable material, a pair of blowout coils of substantially the same core area wound about the magnetizable material and shorted out in the closed circuit position of the interrupter, means for first inserting into series circuit one of the blowout coils, said probe connected to the end of the other of the two blowout coils, and a portion of the arc chute, one end of which is defined by the probe, serving as a transfer arc interrupting section to facilitate the insertion of the said other of the two blowout coils.

12. A circuit interrupter including means for establishing an arc, arc-extinguishing means including an arc chute composed mainly of insulating material including a plurality of spaced insulating portions against the edges of which the arc is forced, a conducting probe disposed intermediate the ends of the arc chute so that insulating portions exist on both sides of the probe, blowout means including a magnetic circuit composed in part of magnetizable material, a pair of blowout coils of substantially the same core area wound about the magnetizable material and shorted out in the closed circuit position of the interrupter, means for first inserting into series circuit one of the blowout coils, said probe connected to the end of the other of the two blowout coils, and a portion of the arc chute, one end of which is defined by the probe, serving as a transfer arc interrupting section to facili-

tate the insertion of the said other of the two blowout coils, and said one of the blowout coils having relatively few turns and the other of the blowout coils having more turns.

13. A circuit interrupter including means for establishing an arc, arc-extinguishing means including an arc chute composed mainly of insulating material including a plurality of spaced insulating portions against the edges of which the arc is forced, a conducting probe disposed intermediate the ends of the arc chute so that insulating portions exist on both sides of the probe, a pair of stationary arc horns at opposite ends of the arc chute, blowout means including a pair of tightly coupled blowout coils connected in series and shorted out in the closed circuit position of the interrupter, one of the arcing horns being connected intermediate the coils, the probe being connected to the end of one of the coils, the arrangement functioning to successively insert the coils into series circuit with the transfer arc of the said one of the coils being interrupted in the portion of the arc chute between the probe and said one of the arcing horns, and said one of the blowout coils having more turns than the other of the blowout coils.

14. A circuit interrupter including a pair of separable contacts for establishing an arc, arc-extinguishing means including an arc chute composed mainly of insulating material including a plurality of spaced insulating portions against the edges of which the arc is forced, a conducting probe disposed intermediate the ends of the arc chute so that insulating portions exist on both sides of the probe, a pair of stationary arc horns at opposite ends of the arc chute, blowout means including a pair of tightly coupled blow-

out coils connected in series and shorted out in the closed circuit position of the interrupter, one of the arcing horns being connected intermediate the coils, the probe being connected to the end of one of the coils, one of the separable contacts being connected to the other end of the other of the coils, the other of the separable contacts being connected to the other arcing horn, the arrangement functioning to successively insert the coils into series circuit with the transfer arc of the said one of the coils being interrupted in the portion of the arc chute between the probe and said one of the arcing horns, and said one of the blowout coils having more turns than the other of the blowout coils.
